STENCILING APPARATUS

Wilbert S. Williams, Columbus, Ohio, assignor
by mesne assignments, to Solar Laboratories,
Beaver, Pa., a corporation of Pennsylvania

Application September 5, 1935, Serial No. 39,305

49 Claims. (Cl. 101—124)

My invention relates to stenciling apparatus. It has to do, more particularly, with an apparatus to be used in stenciling designs or configurations on articles by the process commonly known 5 as the screen-stencil process. More specifically, it relates to a machine for stenciling designs or other markings on glass articles and, especially, on glass articles having a frusto-conical or tapered surface, although it is not necessarily limited thereto.

There have been a number of machines devised in the past for stenciling designs on articles by the screen-stenciling process. Most of these machines have been hand-operated but, 15 lately, there have been attempts to design a satisfactory automatic machine. Most of these attempts have resulted in machines which are cumbersome, of a complicated structure and requiring more than one operator to keep them in operation.

In the decoration of glassware, and particularly such articles as tapered tumblers and footed goblets, one problem that arises is the provision of an apparatus that may be readily and effectively adapted to the decoration of articles having a very slight taper or articles having a substantial taper. In the prior art, some efforts have been made to provide adjustments which will make possible the ready changing of the machine 20 for decorating either slightly tapered articles or articles which are quite substantially tapered. These efforts have contemplated, mainly, the use of stencil screens of flat or plane form, with either the article or the screen swinging so as to cause 25 the article to traverse an arcuate path in contact with the screen during the decorating operation. The point about which either the article or the screen swings is made adjustable to change the arc of the swinging movement to adapt the apparatus to printing on articles of different degrees of taper. Another prior art machine has employed a frusto-conical or tapered stencil of substantially drum-like form. It has been difficult, however, to adjust these machines for decorating articles of different taper. Also, all of 30 these machines have been difficult to load and unload. In most of these machines it is necessary to provide a conveyor for bringing the article into position beneath the screen stencil. 35 However, the use of such conveyors involves certain complications and disadvantages and increases both the cost of the machines themselves and the cost of operation. Also, usually more than one operator is required for operating such 40 machines. These prior art machines have also

been possessed of a number of other disadvantages.

One of the objects of my invention is to provide a machine for stenciling designs or markings on articles by use of the screen process which is 5 automatic in its operation but which is of very simple and compact structure and which can be constructed at a comparatively low cost.

Another object of my invention is to provide a machine of the type indicated which may be 10 operated by a single operator but which will have a large capacity.

Another object of my invention is to provide a machine for stenciling designs or markings on tapered articles and which is so designed that 15 there will be no slippage between the surface of the article and the surface of the stencil and, consequently, there will be no smearing of the design or marking applied to the article.

Another object of my invention is to provide 20 a machine of the type indicated which may be very easily and quickly loaded and unloaded by a single operator and wherein it is not necessary to provide conveyors or other complicated mechanism to position the articles beneath the screen 25 stencil.

In its preferred form, my invention contemplates the provision of a machine embodying a screen stencil which takes the form of a segment of a cone which is caused to travel about 30 the axis of said cone in first one direction and then in the other direction with the article in printing contact therewith during each movement. The screen stencil is so constructed that it is a segment of a cone which has a taper which 35 approximates the taper of the article being decorated but the stencil is preferably of greater diameter than the article. It is adjusted to such a position that the axis of the cone of which it forms a part will intersect the axis of the tapered 40 article at the apex of the said cone and at the apex of the cone which would be formed by continuation of the sides of the tapered article. This results in the movement of the screen stencil and the article in rolling contact in such a 45 manner that the contacting points of the screen and article throughout the length of the article will travel at the same rate of speed with the result that slippage and consequent smearing of the design is avoided.

Furthermore, the segmental conical screen stencil which I utilize is so mounted for movement that the articles may be fed to the machine and removed from the side thereof which is at the side where the operator stands and the 50

operator can remove a decorated article with one hand and immediately place an undecorated article on the chuck with the other hand. In addition, mechanism is provided for moving the screen stencil automatically while the chuck which holds the article is so constructed and operated that the placing of the article thereon will automatically initiate movement of the screen while, at the termination of each movement, the article will be released automatically. The screen stencil is preferably made of cloth and the article is disposed within the arcuate or segmental screen stencil so that if the cloth stencil shrinks and tends to approach the chord of its arc it will merely result in better contact of the screen stencil and the article.

The preferred embodiment of my invention is illustrated in the accompanying drawings wherein similar characters of reference designate corresponding parts and wherein:

Figure 1 is a perspective view of a machine constructed in accordance with the principles of my invention.

Figure 2 is a view mainly in side elevation but partly in section of the machine illustrated in Figure 1.

Figure 3 is a plan view of the machine illustrated in Figures 1 and 2.

Figure 4 is a more or less diagrammatic view of the fluid actuating mechanism and associated parts of the machine.

Figure 5 is a detail in section of the vacuum chuck for supporting the article and the operating mechanism therefor.

Figure 6 is a detail in section of the clutch mechanism which controls reciprocation of the screen stencil.

Figure 7 is a section taken substantially on line 7-7 of Figure 6.

Figure 8 is a perspective view of a portion of the clutch mechanism illustrated in Figure 6.

Figure 9 is a front elevation of a portion of the machine illustrated in Figures 1, 2 and 3.

Figure 10 is a detail in section of a safety device incorporated in the driving mechanism.

Figure 11 is a detail partly in section and in perspective of a portion of the arcuate member which supports the screen stencil.

Figure 12 is a detail in perspective of part of the means employed for controlling the squeegee.

Figure 13 is a perspective view of a modified form of my machine.

Figure 14 is a detail, partly in section and partly in side elevation, of the machine illustrated in Figure 13.

Figure 15 is a sectional view illustrating how a poppet valve may be provided for operating the master valve.

Figure 16 is a sectional view taken substantially on line 16-16 of Figure 15.

Figure 17 is a perspective view, partly broken away, of a unit mounted at each end of the screen stencil for preventing the paint or printing material from accumulating at the ends of the screen stencil.

Figure 18 is a sectional view showing the unit illustrated in Figure 17 in one position during operation.

Figure 19 is a view similar to Figure 18 showing the unit in another position during operation.

Figure 20 is a plan view illustrating how one of the units is positioned at each end of the screen stencil.

With reference to the drawings, and particularly to Figures 1, 2 and 3, I have illustrated my

machine as comprising mainly an article supporting chuck 1, screen and squeegee printing mechanism 2 disposed above the article, clutch mechanism 3 for controlling the reciprocation of the screen stencil transversely of the article and for 5 rotating the article about its own axis, and a double unit cylinder and piston mechanism 4 for controlling the clutch mechanism 3. All of these various units are carried by a supporting frame 5 which is adjustably mounted on a supporting 10 table 6. The frame 5 carries at its lower end a curved plate 7 which rests in a curved cradle 8. The plate 7 is secured in position in the cradle by means of bolts 9 which pass through slots 10 formed in the plate. It will be apparent that the 15 bolts and slots will permit adjustment of the plate 7 to various positions in the cradle so that the main portion of the machine, that is all the units carried by the frame 5, may be adjusted to any desired position relative to the horizontal and 20 secured in adjusted position.

The supporting table 6 has a rear extension 11 which carries an electric motor 12. This motor drives a pulley 13 through the intermediary of a worm and worm wheel unit 14. The pulley 13 25 drives a pulley 15 which is disposed adjacent the forward edge of the table by means of a belt 16. The pulley 15 is keyed on the outer end of a shaft 17. This shaft 17 is made in two sections which are rotatably mounted in suitable bearings and it 30 extends to a point within the clutch housing 18 of the clutch unit 3.

In order to avoid injury to the machine in case a part or parts thereof bind or become inoperative for any reason, I interpose a safety device 19 between the two sections of the shaft 17. This safety device is illustrated best in Figure 10. As shown, one section 20 thereof is keyed to the end of one of the sections of the shaft 17. Another section 21 is keyed to the adjacent end of the 40 other section of the shaft. The two sections are normally caused to rotate together by means of a plurality of balls 22 which are normally pressed into the sockets 23, carried by the section 20, by means of springs 24 carried by the section 21. 45 However, if for any reason the driven section of the shaft 17 will not rotate, the balls 22 will be forced inwardly against the springs 24 and out of the sockets 23 in the section 20, permitting the section 20 and the section 21 to rotate relative to 50 each other and, thus, preventing injury to the machine. The springs 24 are of sufficient strength to normally maintain the balls 22 in the sockets 23. They are carried in socket members which are carried by a member 25 that is screwed on the section 21 and held in adjustable position thereon by a set screw 21a. The member 25 may be adjusted on the section 21 to vary the force 55 exerted by the springs and to keep the balls 22 seated in the sockets 23.

As previously stated, the shaft 17 extends within the housing 18 which contains the clutch mechanism adapted to control the reciprocating movements of the screen stencil and rotation of the article. As shown in Figures 2, 4 and 6, the inner end of this shaft 17 has a bevel gear 26 keyed thereon. This gear 26 drives a bevel gear 27 in one direction and a second bevel gear 28 in an opposite direction. These gears 27 and 28 are disposed within the clutch housing and form part 70 of the clutch mechanism. They are loosely mounted for rotation on a hollow shaft 29 which extends through the clutch housing. The gears 27 and 28 are constantly driven by the gear 26 and normally rotate on the shaft 29. Each of the 75

gears 27 and 28 has a chamber 30 formed therein in which is disposed mechanism 31, that is carried by shaft 29, which may be operated to clutch the shaft to the corresponding bevel gear. The mechanism for clutching the gear 27 to the shaft 29 is the same as that for clutching gear 28 to shaft 29 and, therefore, a description of one will suffice.

This mechanism 31 is illustrated best in Figures 7 and 8. It is disposed within the drum-like housing 30 of the gear. It comprises an arm member 32 which is keyed to the shaft 29. This arm member has pivoted to each end thereof a shoe 33 as at 34. Each shoe 33 is made of an inner and outer section both of which are pivoted to the arm 32. The inner section 33a may be spaced apart from the outer section to any desirable extent by adjustment of wedge bolt 35 which is disposed between the two parts. A spring 36 is provided for normally urging each shoe 33 to swing inwardly towards shaft 29. This spring is connected at one end to the pivot 34 and at its opposite end to a member 37 which is pivoted to the outer section of the shoe and has an extension 38. This extension 38 contacts with a small pin 39 on the inner section 33a. It will be understood that the spring 36 not only tends to swing the entire shoe 33 inwardly but also tends to keep the inner section 33a of the shoe in contact with the outer section thereof since the member 37 tends to swing around its pivot and by means of extension 38 and pin 39 to force the inner section 33a against the outer section. However, as previously stated, the wedge bolt 35 limits the extent to which these two members are spaced apart.

As shown in Figure 6, the inner surface of each of the sections 33a of the shoes 33 is beveled as indicated at 40. A sleeve member 41 which has frusto-conical ends is mounted on the shaft 29 in such a manner that the shaft may freely rotate therein. Also the sleeve may be moved longitudinally of the shaft. The frusto-conical ends of the sleeve 41 are adapted to be moved into the frusto-conical sockets formed within the shoe members 33 by the tapered surface 40. However, both ends of the sleeve are normally out of the sockets so that the clutch will normally be in neutral, as illustrated in Figure 6. The shoe members 33 carry brake bands 42 that are adapted to frictionally engage the inner peripheral wall of the drum-like chambers 30. When the frusto-conical end of the sleeve 41 is moved between the two shoe members 33 of one of the units 31, it spreads the shoes apart causing the bands 42 to engage the wall of the chamber 30 and, consequently, causes the bevel gear to rotate with the shaft 29. The sleeve 41 may be moved longitudinally of the shaft 29 to cause either of the bevel gears to be clutched thereto by means of a lever 43 that extends upwardly from the housing and is pivoted thereto. It will be apparent that when the bevel gear 27 is clutched to the shaft 29, the shaft will rotate in one direction and when the bevel gear 28 is clutched to the shaft, the shaft 29 will rotate in an opposite direction.

The shaft 29 extends forwardly to the front end of the machine. This shaft 29 is adapted to cause the screen stencil support to reciprocate and also to rotate the article about its axis. The forward end of the shaft 29 carries the chuck 1, as illustrated best in Figures 2, 4 and 5. This chuck comprises a collar 44 which is keyed to the shaft 29 adjacent its forward end. One end of a spring 45 abuts this collar 44 and the other end of the

spring abuts the spider-like structure 46 which is disposed forwardly of the collar 44 and is free to slide on the shaft 29. A second structure 47 identical with that just described is disposed on the shaft at a point spaced a short distance rearwardly of the first structure. However, the arms of the spider-like member of this structure are longer than those of the other. The article is adapted to be placed on the chuck, as illustrated in Figures 2 and 5. It will be firmly supported thereon since the spider-like structures are free to move inwardly to compensate for variations in the taper of the article.

As previously stated, the shaft 29 is hollow and has a passage way 48 extending from one end thereof to the other. This passageway is adapted to be connected to a vacuum pump. The forward end of the shaft 29 has a suction cup 49 which is preferably formed of rubber mounted thereon. The edge of this suction cup 49 is adapted to engage the bottom of the article as illustrated in Figure 5. The suction cup is removably held in position by a collar 50 threaded into the forward end of the shaft 29. The shaft 29 has a rod 51 mounted therein for longitudinal movement. This rod is normally urged outwardly by a spring 52 disposed in a chamber 53 into which the rear end of the rod extends. This chamber 53 is formed in a valve housing 54 which is bolted or otherwise secured to the rear end of the frame 5. This spring 52 engages a collar 55 on the rod. The rear end of the spring is disposed in a socket formed in the forward end of a plunger 56 which is slidably mounted in the chamber 53. This plunger 56 has an annular groove 57 formed therein. When the rod is pushed inwardly as illustrated in Figure 5, the groove 57 is in alignment with an opening 58 formed in the housing 54 and to which a vacuum line 58a is connected. It is also in alignment with a duct 59 which leads forwardly through the housing 54 and communicates with the passage 48 in the hollow shaft 29 by means of an opening 60. Thus when the rod 51 is in its innermost position, the passage 48 is in communication with the vacuum line connected to the opening 58 in the housing 54. The plunger 56 may, however, be moved into a position where the groove 57 will align with openings 61 and 62 that will permit air from the atmosphere to enter through the passage 59, opening 60 and into the passage 48. The rod 51 extends forwardly through the collar 50 and projects from the shaft. It is loose in the collar 50 so that air may be exhausted from within the vacuum cup 49 by means of the vacuum line connected with the passage 48. The forward end of the rod has a sleeve member 51a threaded thereon as at 51b so that the length of the rod may be varied. The extreme forward end of the rod has a button 51c of rubber adapted to contact with the bottom of the article.

When the article is not in position on the chuck, the rod will extend forwardly a considerable distance past the outer edge of the cup 49 as illustrated in Figure 4. At this time, the plunger 56 will be in such a position that air from the atmosphere will be permitted to enter the passage 48. As soon as an article is positioned on the chuck, the bottom thereof will strike the forward end of the rod and will move it rearwardly. This will move the plunger rearwardly and cause communication to be established between the vacuum line and the passage 48. Consequently, the air will be exhausted from the passage 48 and the interior of the vacuum cup 49 and the article will

be held on the chuck by the vacuum. I provide means, to be described subsequently, for automatically releasing the vacuum and for causing the rod 51 to be forced forwardly in order to release the article from the chuck.

Behind the chuck 1, the shaft 29 has a gear 63 keyed thereon. This gear 63 meshes with an arcuate rack 64 as illustrated in Figures 2, 4 and 9. The rack 64 is carried on the rear surface 10 of an arcuate screen stencil supporting member 65. This screen stencil supporting member is supported on the machine in such a manner that it may be reciprocated by the gear 63 which engages the rack 64. As shown best in Figures 15 2 and 3, the member 65 is mounted for reciprocation in a cradle formed by a plurality of rollers 66. These rollers engage the edges of the member 65. I preferably provide a pair of rollers that engage the top edge of the member 20 65 and two pairs of rollers that engage the bottom edge thereof. In other words, the member 65 will be supported at three points as illustrated best in Figure 3. The rollers 66 are supported on arms 67 which are suitably secured to a plate 25 68 that has arms with curved rear surfaces. These arms are adjustably supported in a cradle 69 by means of bolts and slots 70. The cradles 69 are formed in arms carried by a member 71. This member 71 has a curved rear surface 72 30 which fits into cradles formed in the forward surfaces of arms on a member 73. The member 71 is adjustably held in the cradle in the member 73 by means of slots and bolts 74. The member 73 has arms on a vertically disposed extension 35 75 extending upwardly therefrom which has a projection on its rear surface that slides in a guideway formed in a vertically disposed plate 76 that is mounted on the clutch housing 18. The member 75 is adjustably secured to the member 40 76 by bolt and slot connections 77. Thus, the member 75 may be vertically adjusted on the member 76 to raise or lower the screen stencil supporting member 65. The member 68 may be 45 adjusted in its cradles and the member 71 may be adjusted in its cradles to tilt the support 65 to any desired position. The member 65 may either be disposed in a vertical plane or it may be tilted to any desired angle. This adjustment is important for reasons which will appear hereinafter. The outer edges of the gear teeth of 50 the rack 64 are rounded as at 78 (Figure 1) so that the gear 63 will firmly mesh with the rack 64 regardless of the tilted position of the member 65.

55 The member 65 has a forwardly projecting arm 79 secured thereto adjacent each end thereof. Each arm 79 has a lug 80 formed on its rear end which has a curved rear surface that fits on a correspondingly curved surface formed on 60 a lug member 81 as illustrated at 82. The member 80 is secured to the member 81 by means of bolt and slot connection 83. Because of this connection, the member 79 may be adjusted to any desired position relative to the horizontal 65 and secured in adjusted position. The lug 81 is secured to the member 65 by a bolt and slot connection 84 and the member 65 is provided with a plurality of bolt openings 85 spaced therealong so that the lug 81 may be moved to various positions. The forward ends of the arms 79 are tied together by a curved member 86.

70 The arms 79 are adapted to support the screen stencil 87. As shown, this stencil comprises a screen which is preferably made of silk that is 75 stretched and fastened to a wooden frame 88.

This frame 88 has plates 89 secured thereto at both ends and they project outwardly therefrom. These plates are adapted to be received between four lugs 90 formed on each of the arms 79. The two top lugs 90 have screw bolts 91 threaded downwardly therethrough and the two bottom lugs have screw bolts 91 threaded upwardly therethrough. Thus the plates 89 may be clamped between the bolts 91 and these bolts may be adjusted to obtain slight vertical adjustment of 10 the screen stencil relative to the arms 79.

As previously stated, the screen 87 is preferably in the form of a segment of a cone. This is important when it is desired to decorate tapered articles. The taper of the screen stencil 15 should be approximately the same as the taper of the article in order to avoid slippage between the surface of the screen stencil and that of the article but the screen stencil is preferably of greater diameter than the article. However, 20 in order to avoid slippage, it is also necessary to tilt the screen stencil supporting member 65. The member 65 should be tilted to such an extent that when it is reciprocated, the segmental screen stencil will move in first one direction 25 and then the other about its axis line, which is the axis of the cone of which it forms a part, which intersects the axis of the article at the common apex of the cone of which the screen stencil forms a part and the cone which would 30 be formed by continuation of the sides of the article.

If the taper of the articles being decorated by the machine varies considerably from time to time, the screen stencil should be replaced with 35 a screen stencil having substantially the same taper as the articles to be decorated. Also, the member 65 should be adjusted to a different tilted position so that the segmental screen will move back and forth about its axis line which intersects the axis of the article, as described above, 40 in order to avoid slippage. The member 65 may be readily adjusted, as previously described, and the screen 76 may be readily removed and replaced by a different screen.

45 In order to force the paint or other printing material through the screen stencil, I provide the squeegee mechanism 2, as previously described. This squeegee mechanism comprises a forwardly extending arm 92 which has its rear end secured to a vertical member 93 that is slidably mounted for vertical movement on a member 94. This member 94 is secured to an L-shaped bifurcated structure 95 that is pivotally secured as at 96 to the member 68 which carries 55 the member 65. The member 92 has a slot 97 formed therein which receives the upper end of a support 98 that has the squeegee member 99 secured to its lower end. The member 98 is pivotally secured to the arm 92 as at 100 by a 60 pivot pin which may be disposed in any of a number of openings 101 along the arm 92. The squeegee 99 embodies two plates 102 which clamp a blade 103 of rubber or other suitable material therebetween. The squeegee is adapted to normally rest on the upper surface of the screen stencil and weights 104 are provided on a structure 105, which is bolted to the forward end of arm 92, in order to cause the squeegee to bear against the screen stencil with the desired 70 amount of pressure.

The squeegee supporting member 98 has an upwardly extending member 106 secured to the upper end thereof. This member is slotted at its upper end as at 107. A threaded rod 108 passes 75

through this slot. This rod 108 has its rear end mounted in the upper end of member 93. Disposed in surrounding relation to the rod 108 at opposite sides of the member 106 are springs 109. 5 These springs oppose each other. The force which they exert may be varied by adjusting nuts 110 which are threaded on the rod. The springs will permit the squeegee to rock about the pivot point 100 in case of variations in the articles. Also, the springs may be adjusted so 10 that one exerts more force than the other and thereby tend to rock the squeegee about the pivot point in one direction. This would cause one end of the blade 103 to press down on the screen 15 stencil with more force than the other end thereof. This adjustment may be desirable if the screen is not exactly the same taper as the article for slightly distorting the screen stencil so that it will assume substantially the same taper as the 20 article.

It will be apparent that the member 65 will be reciprocated, causing movement in first one direction and then the other of the screen stencil relative to the article and also relative to the 25 squeegee. This will cause the squeegee to wipe over the surface of the screen stencil. During this movement, the outer end of the squeegee supporting arm 92 is supported by means of the structure 105 which carries a roller 111 on its lower end that is spaced above member 86. The member 86 is made of an angle iron and has an 30 upstanding flange 112. The roller 111 is mounted on the outer end of a shaft 113 which is slidably mounted in a bearing 114 on the lower end of member 105. A bar 114a is pivoted to the upper 35 end of member 105 as at 115. The lower end of this bar bears against the outer end of the roller shaft 113. A spring 116 is provided which tends to swing the bar 114a inwardly. This tends 40 to push the roller shaft 113 inwardly.

It will be apparent that when the screen stencil is moved in one direction to the extent of its movement, the paint or printing material will be scraped over the surface of the stencil and the greater portion thereof will be carried to one end of the stencil. When the screen is then moved in the opposite direction, the paint piled up by the stencil would not be carried along towards the other end of the stencil unless some means were provided for causing the squeegee to get to the opposite side of the small pile of paint. In order to always keep paint in front of the squeegee, regardless of the direction of movement of the screen stencil, I provide the structure to be described now. This structure comprises a track member 117 that is mounted on the member 86 adjacent each end thereof. As shown in Figure 12, this member 117 has an inclined track 118 formed thereon directly adjacent the flange 112 of member 86. Directly adjacent the track 118 is a steeper track 119. The upper surface of the track 119 is at a slightly lower level than the upper surface of the track 118 so that a shoulder is formed at 120. The vertical 45 surface of this shoulder is curved as indicated. When the screen stencil has moved almost to the extent of its movement in one direction, the roller 111 will begin to ride up on the track 118. At this time, there will be a pile of paint accumulated on the one side of the squeegee. As the roller 111 rides up on the track 118, the squeegee will be raised since the arm 92 will pivot about the point 96. Continued movement causes the squeegee to be raised above the point. The 50 roller 111 will then drop from the track 118 onto

the track 119. At this time, the squeegee will be at the opposite side of the pile of paint but will be spaced above the screen stencil. Now if the screen stencil is moved in the opposite direction, the roller 111 will contact with the shoulder 120 5 and continued movement will cause the roller to move forwardly a slight distance so that it will then roll along track 119. It will drop down off the track 119 and, consequently, the squeegee will again be in contact with the stencil and the 10 paint will again be in front of the squeegee. The spring 116 permits the necessary lateral movement of the roller 111 in moving from the track 118 to the track 119. The path of movement of the roller is illustrated by the arrows in 15 Figure 12.

It will be understood that the screen stencil, although in the form of a segment of a cone, may have a radius as long as desired. It may have a radius a number of times longer than 20 that of the article but it should have substantially the same taper as the article. The wood frame on the stencil will keep the paint from running off the surface. It will also be noted that the article is disposed within the arcuate 25 screen stencil. This is important because the silk screen due to shrinkage tends to draw inwardly towards the chord of the arc of the stencil. However, this will be advantageous since 30 the article is disposed within the arc and it will merely tend to cause the screen to more firmly contact with the article.

I will now describe the mechanism that operates the clutch lever 43 which, in turn, operates the clutch mechanism that controls rotation of 35 the article and back and forth rotative movement of the screen stencil. This mechanism is illustrated best in Figures 1, 2 and 4. I provide a shelf 121 which is supported in an inclined 40 position on suitable supports secured to the clutch housing 18. This shelf has a cylinder 122 supported on its upper end and a cylinder 123 supported on its lower end. The cylinder 122 has a piston 124 disposed therein which has a piston rod 125 secured thereto which projects 45 from the cylinder. The cylinder 123 has a piston 126 therein having a piston rod 127 that projects from the cylinder. The shelf 121 has a slot 128 formed therein substantially midway between the ends thereof. The upper end of the 50 clutch lever 43 projects up through this slot.

The piston rod 125 and the piston rod 127 extend towards each other. The outer end of the rod 125 has an L-shaped latch 129 pivoted thereto as at 130. The outer end of the piston rod 55 127 has an L-shaped latch 131 pivoted thereto as at 132. The latch 129 has a notch 133 formed therein adjacent the outer end thereof and the latch 131 has a similar notch 134 formed therein. These notches are adapted to engage an 60 extension 135 on the upper end of the lever 43. The outer end of each of the latches 129 and 131 is provided with a cam surface 136. Springs 136a are provided for normally swinging the latches downwardly. In order to cause the 65 latches 129 and 131 to swing upwardly about their pivots at the proper time, I provide a pair of plates 137 which support a pin 138 at one end thereof and a pin 139 at the opposite end thereof. The pin 138 is adapted to be engaged by 70 the upstanding portion 140 of the latch 129 and the pin 139 is adapted to be engaged by the upstanding portion 141 of the latch 131. The upstanding portion 140 engages the pin 138 when the piston rod 125 is in its outermost position, 75

as indicated in Figure 4. The upstanding portion 141 of latch 131 engages the pin 139 when the piston rod 127 is in its outermost position as indicated in Figure 4.

5 I provide means to be described subsequently for causing the pistons 124 and 126 to reciprocate in their respective cylinders. When no article is on the chuck, the pistons 124 and 126 will be in their outermost positions in the cylinders, 10 as indicated in Figures 1 and 4, as will be better understood hereinafter. Assuming that the pistons are in the positions in the cylinders illustrated in Figures 1 and 4, it will be apparent that since the piston rod 125 is in its outermost 15 position, the portion 140 of the latch 129 will be in contact with the pin 138 and, consequently, the latch 129 will be swung around its pivot to such an extent that the notch 133 will be disengaged from the extension 135 on the upper end 20 of lever 43. Also, since the piston 126 is in its outermost position in its cylinder, the notch 134 of the latch 131 will be out of engagement with the extension 135 on the clutch lever 43. Thus, 25 when no article is on the machine, both the latch 129 and the latch 131 will be out of engagement with the clutch lever 43 and, consequently, the clutch will be in neutral position.

30 However, if air is admitted into the cylinder 122, in a manner to be described later, the piston 124 will move to the opposite end of the cylinder 122 causing the piston rod 125 to be retracted into the cylinder and will permit the latch 129 to swing downwardly and engage the upper end of the clutch lever 43. The other latch 131 will be caused to engage the upper end of the lever 43 in the same manner by inward movement of the piston 126 in the cylinder 123. However, as will be described more fully hereinafter, when one of the latches is in engagement with the clutch lever the other latch is out of engagement with said lever. The initial movement of either of the pistons from the position indicated in Figure 4 causes the latch mechanism to which such piston is connected to become engaged with the clutch lever. Further movement of such piston causes the clutch lever to swing in a corresponding direction and to operate the clutch. Thus, one cylinder and piston mechanism swings the lever 43 in one direction and the other cylinder and piston mechanism swings the lever 43 in an opposite direction.

When the clutch lever 43 is moved to the left to the extent of its movement, as indicated in Figure 2, the bevel gear 28 will be clutched to the shaft 29. Consequently, the article will be rotated in one direction and the screen stencil will be moved in one direction transversely of the article. However, when the clutch lever 43 is moved to the right to the extent of its movement, the bevel gear 27 will be clutched to the shaft 29. Consequently, the article will then be rotated in an opposite direction and the screen stencil will move in an opposite direction relative to the article.

65 I will now describe the various valves and associated parts together with the fluid system which controls operation of the machine. With reference to Figures 1, 2 and 4, I illustrate a main air line 142 which is connected to a master valve 143. The main air line is connected to this valve 70 at one side thereof and a continuation thereof 142a leads from the opposite side of the valve. The master valve 143 is mounted below the valve housing 54. It comprises a main chamber 144 having a piston 145 therein with a piston rod 146 75 projecting through the rear wall of the valve housing.

ing. The piston 145 is normally kept in the rear portion of the chamber 144 by a spring 147. The rod 146 has a groove 148 which may be brought into alignment with the ends of the lines 142 and 142a connected thereto to permit free passage of air through the line into line 142a, as illustrated in Figure 2. However, because the spring 147 tends to keep the piston 145 in its rearmost position, the groove 148 is normally out of alignment with the lines 142 and 142a, as indicated in Figure 4, and, consequently, stops flow of air therethrough. The forward wall of the chamber 144 is provided with an air escape opening 149 so that the piston 145 may be moved forwardly in the chamber 144 by mechanism to be described. A duct 150 which leads to the atmosphere and is under the control of a spring pressed ball valve 151 is provided so that when the piston 145 moves into the forward end of the chamber 144, the valve 151 will be opened by the suction developed by movement of the piston, and air will be drawn into the chamber 144 through the duct 150. When the piston is permitted to move rearwardly under the influence of spring 147, the air in the chamber 144 will prevent rapid movement of the piston to its rearmost position, due to the fact that the valve 151 will close and the air will be permitted to escape very slowly through a small opening 152. As will be explained more in detail, the piston rod 146 is moved inwardly until the groove 148 aligns with the lines 142 and 142a and is then quickly released so that the spring 147 will gradually return it to its original position. This permits a puff of air to flow through the main line past the master valve and into line 142a. An oil housing 153 is mounted in the line 142 for feeding oil throughout the fluid system.

The line 142a branches into two branches which are connected to the cylinders 122 and 123. However, two valves 154 and 155 of identical structure control the flow of air through these branches to the cylinders. A line 142b leads from the line 142, at a point before it reaches the master valve 143, and it branches into two branches which are connected to the cylinders 122 and 123 at the ends opposite to where the branches of the line 142a are connected thereto. The valves 154 and 155 also control flow of air through these branches to the cylinders. Each valve includes a plunger 156 which is normally urged outwardly by a spring 157. Each plunger is moved inwardly against the force of the spring when the outer end thereof contacts with a cam member 158 secured to the rear surface of the screen stencil supporting member 65. A cam member 158 is disposed adjacent each end of the member 65 and is adjustably mounted in an arcuate groove 159 of T-shaped cross section.

The valve 154 has a transverse duct 154a formed therein and one branch of the line 142a is connected to both ends of said duct. It also has a transverse duct 154b formed therein and one branch of the line 142b is connected to both ends of said duct. The plunger 156 of the valve 154 is provided with a groove 1540a formed therein and a groove 1540b which are adapted to be brought into alignment with the transverse ducts 154a and 154b, respectively, when the plunger is in its innermost position, as indicated in Figure 4. The line 142a leads from the valve 154 to the piston rod end of the cylinder 122 where it is connected thereto as at 158a. The line 142b leads from the valve 154 to the closed end of the cylinder 123 where it is connected thereto as at 158b.

The valve 155 has a transverse duct 155a formed 75

therein which has both ends connected to the line 142a and has a transverse duct 155b formed therein which has both of its ends connected to the line 142b. The plunger 156 of this valve has a groove 1550a and a groove 1550b formed therein which are adapted to be brought into alignment with the ducts 155a and 155b, respectively, when the plunger 156 is in its innermost position. The line 142a leads from the valve 155 to the piston rod end of the cylinder 123 where it is connected thereto as at 160. The line 142b leads from the valve 155 to the cylinder 122 where it is connected thereto as at 161.

It will be apparent that the lines 142a are connected to the piston rod ends of the cylinders 122 and 123 and that the lines 142b are connected to the opposite ends of the cylinders 122 and 123. Furthermore it will be apparent that when the plunger 156 of valve 154 is in its innermost position, as illustrated in Figure 4, and the master valve is opened by placing an article on the chuck, the air from the line 142 will be permitted to flow through the master valve into the line 142a, duct 154a of valve 154, again through the line 142a, 25 and then into the piston rod end of cylinder 122. At the same time, air will flow through the line 142b from the line 142, through the duct 154b in valve 154, again through the line 142b and into the closed end of cylinder 123. Thus, both the piston 30 tons 124 and 126 will be in the positions indicated in Figure 4 if the valve 154 is open and no article is on the machine, as illustrated in this figure. All of the lines are provided with very small air escape openings 162 which permit exhaust of air from the ends of the cylinders at the proper time, as will be explained more in detail hereinafter.

When the plunger of the valve 154 is in its innermost position, as illustrated in Figure 4, the plunger of the valve 155 is in its outermost position. Consequently, the transverse ducts 155a and 155b formed therein are closed and flow of air through the line 142a and the line 142b, connected to said valve, is interrupted. Operation 45 of the valves 154 and 155 is controlled by movement of the member 65. When it is in the position illustrated in Figure 4, the valve 154 is open and the valve 155 is closed. However, when it is reciprocated in the other direction to the extent 50 of its movement, the plunger 156 of valve 155 will be forced inwardly to open said valve while the plunger 156 of the valve 154 will be in its outermost position and said valve will be closed.

At this time, if the master valve 143 is opened 55 by placing an article on the chuck, the air will flow from the line 142 through valve 143, line 142a, through transverse duct 155a in the valve 155, again through line 142a to the piston rod end of the cylinder 123. The air will also flow from the line 142 through line 142b through the transverse duct 155b in valve 155, and again through line 142b to the closed end of the cylinder 122. At the same time, since the valve 154 is closed, 60 flow of air to the opposite sides of the cylinders through the lines 142a and 142b that are connected to valve 154 is interrupted.

The closed ends of the cylinders 122 and 123 may be connected together by a valve controlled 65 conduit 142c under the control of a manually operable valve 163 which is normally closed. This valve may be opened in order, at any time, to get the pistons in the positions illustrated in Figure 4, but the valve 154 or 155 must also be opened.

75 The main line 142 has another branch 142d

which is connected to a vacuum line 58a that is connected to a vacuum pump and to the valve 52. This line 142d is under control of a manually operated valve 164 which is normally closed. This valve may be opened and a valve 165 in the suction line 58a may be closed to permit air under pressure to flow through the line 142d, line 58a, opening 58, duct 59, opening 60, and then through the passageway 48 formed in the hollow shaft 29, in order to blow out any dirt that accumulates in the hollow shaft.

I will now describe the mechanism that controls movement of the plunger 56 of valve 52 and the plunger or piston rod 146 of the valve 143. This mechanism is illustrated best in Figures 1 and 2. 15 The outer end of the piston rod 125 has a bifurcated member 166 pivotally secured thereto by the pivot 140. This member 166 has a rearwardly extending thrust rod 167 secured to its upper end. The rear end of this rod 167 is pivotally secured to a lever 168 as at 169. This lever is pivoted to a support 170 as at 171. This support 170 is bolted to the housing of valve 52. The lower end of the lever 168 has an extension 173 thereon which has a beveled edge. The piston rod 127 also has pivotally secured thereto at 132 a bifurcated member 174 which has a thrust rod 175 secured to the lower end thereof. This thrust rod extends rearwardly and is pivotally connected to a lever 176 which is pivoted for movement 20 about the pivot point 171. This lever 176 has an extension 177 with a sharp lower edge.

The plunger 56 has a block 178 (Figure 1) formed on its outer end. This block is slotted as at 179. On one side of this block, a dog 180 is pivoted. This dog is normally urged upwardly by a spring 181 but its upward movement is limited by a pin 182 engaging an extension on its outer end. The upper edge of this dog is curved as at 183 and has a sharp corner 184 at its upper and outer edge. A second dog 185 of identical structure is pivoted on the opposite side of the block. The corner 184 of the dog 180 is adapted to be engaged slightly by the extension 173 of the lever 168 when the lever swings in such a manner that the lower end swings rearwardly. However, the dog 180 will pivot downwardly slightly in order to permit passage of the extension 173 and then pivot upwardly so that the point 184 will be in front of the extension 173. The lever 176 and the dog 185 will cooperate in a similar manner.

The block 178 has a third dog 186 (Figures 2 and 4) pivoted thereto and disposed in the slot 179. However this dog is reversed relative to the others and is pivoted for upward swinging. It cooperates with an extension 187 on a pivoted lever 188 which is pivoted at the rear of the valve 143. A spring pressed plunger 189 tends to swing the upper end of this lever 188 outwardly. The lower end of this lever 188 however engages the outer end of the piston rod 146 which is normally urged outwardly by the spring 181.

The mechanism just described operates in the following manner. Assuming the parts are in 65 the positions illustrated in Figure 2, it will be apparent that the plunger 56 is in its outermost position. During movement into such outermost position the dog 186 engages the extension 187 on the lever 188 and causes said lever to swing about 70 its pivot forcing the piston rod 146 forwardly and operating the valve 143 to permit a puff of air to flow into the line 142a. The plunger 56 is moved into the position indicated in this figure merely by placing the article on the chuck, 75

through the medium of the rod 51. When the plunger is moved rearwardly a sufficient distance, the end of the extension 187 will slip off the corner of the dog 186, permitting the upper end of lever 188 to swing forwardly and allowing the rod 146 and piston 145 to move rearwardly closing the valve 143. When the parts are in the positions illustrated in Figure 2 the extension 177 on lever 176 will be out of engagement with the dog 185. 5 The extension 173 on the lever 168 will be in its rearwardmost position in engagement with the dog 183.

If the piston 124 is moved to the other end of the cylinder from the position indicated in Figure 2, the rod 167 which is connected to the piston rod 125 will cause the upper end of the lever 168 to swing rearwardly. The extension 173 of the lever is in engagement with the dog 188 and, consequently, it will move the plunger 56 forwardly until extension 173 swings to such a point that it will be disengaged from the dog. If the piston 126 is moved to the opposite end of the cylinder 123, piston rod 127 will move to the right (Figure 2) and the rod 175 will cause the lever 176 10 to swing rearwardly until extension 177 snaps behind dog 185.

I will now describe the operation of the entire apparatus. Assuming that the various parts of the operating mechanism of the machine are in the positions illustrated in Figure 4, it will be apparent that there is no article in position on the machine and that the member 65 has been moved to such a position that the valve 154 is open and the valve 155 is closed. The clutch, at 15 this time, is in neutral position because the main air pressure flows from the line 142, through line 142b, through valve 154 and into the closed end of cylinder 123, forcing the piston 126 into the position indicated in this figure and, consequently, causing the latch 131 to be disengaged from the upper end of the clutch lever 43. The piston 124 will also be in the position indicated 20 in this figure because when the valve 155 was previously opened by movement of the member 65 25 into the opposite position from that indicated in this figure, air flowed from the constant pressure line 142, through line 142b, through valve 155 into the closed end of cylinder 122, forcing the piston 124 into the position indicated in this figure and, consequently, disengaging the latch 129 from the upper end of the clutch lever 43. Thus, with 30 the various parts in the positions indicated in this figure, the clutch will be in neutral and the shaft 29 will not be rotated and, consequently, the member 65 will remain stationary and the chuck 35 will be stationary.

However, as soon as an article is placed on the chuck, the machine will again be started in operation. In positioning the article on the chuck, the rod 51 is forced rearwardly. This moves the plunger 56 rearwardly. This causes communication to be established between the vacuum line 58a and the passageway 48 in the hollow shaft 29. Consequently, the vacuum force will hold the article in position on the chuck. Rearward movement of the plunger 56 also operates the valve 143 through the medium of lever 188 and when the valve 143 is opened, air flows for a short period from the line 142 into the line 142a until the valve 143 gradually reaches closed position which will occur automatically. Since the member 65 is in such a position at this time that the valve 154 is open, the air will flow from the line 142a through the valve 154 and into the piston rod end of the cylinder 122. This will force the

piston 124 into the opposite end of the cylinder which will cause the latch 129 to engage the upper end of the clutch lever 43 and will swing this lever to the left, as indicated in Figure 2. This causes the bevel gear 28 to become clutched to the shaft 29 and drive the shaft in one direction. When the shaft is driven, it immediately causes movement of the member 65 through the medium of gear 63 and rotation of the article in one direction. The valve 154 will be immediately closed. 10 The member 65 will continue to move until the cam 158 at the opposite end thereof strikes the plunger 156 of valve 155 and opens this valve. At this time, air will flow from the line 142, through line 142b and through valve 155 into the closed end of cylinder 122 and again force the piston 124 to the position indicated in Figure 4 which causes movement of the clutch lever 43 again into the position indicated in this figure and the latch 129 to be disengaged 15 therefrom. The clutch will again be in neutral and rotation of the shaft 29 and, consequently, movement of the member 65 and rotation of the article ceases. Movement of the piston 124 back to the position illustrated in Figure 4 causes the rod 167 connected thereto to move rearwardly which, in turn, causes the lower end of lever 168 to swing forwardly. Since, as indicated in Figure 2, the lower end of the lever is in engagement with the dog 180, before the 20 piston starts to move back into the position indicated in Figure 4, such movement of the piston also causes forward movement of the plunger 56 which, in turn, causes forward movement of the rod 51 and also cuts off the vacuum supply to 25 the chuck. The forward end of the rod 51 will strike the bottom of the tumbler and will automatically disengage it from the chuck so that the operator may remove it. Forward movement of plunger 56 also causes the extension 187 on member 188 to again engage dog 186, as shown in 30 Figure 4.

In order to again start the machine in operation it is necessary to place another article on the chuck. This causes the vacuum chuck to 45 again be operated to hold the article in place. Also, it causes opening of the valve 143 for a short period again. Since, however, valve 155 is open and valve 154 is closed at this time, the air will flow for a short period into the line 142a, 50 through valve 155 and into the piston rod end of cylinder 123, forcing the piston 126 into the opposite end of the cylinder from that indicated in Figure 4. This causes the latch 131 to engage the upper end of the clutch lever 43 and to swing 55 the clutch lever to the right (Figures 2 and 4). This causes the gear 27 to be clutched to the shaft 29 and brings about rotation of the shaft. Rotation of the shaft causes rotation of the article about its axis and movement of the member 65 60 in the opposite direction which again closes valve 155. Movement of the piston 126 into the end of the cylinder 123 opposite to that indicated in Figure 4 also causes rearward movement of the rod 175 (Figure 2) and rearward swinging of the 65 lever 176. The lever will swing until it becomes engaged with the dog 185. The article will continue to rotate and the member 65 will continue to move until it again reaches the position indicated in Figure 4 at which time the valve 154 will 70 again be opened. At this time air will flow from line 142, through line 142b, through valve 154 and into the closed end of cylinder 123 and again force the piston 126 back to the position indicated in Figure 4. This causes the clutch lever 75

43 to move back into neutral position and, consequently, rotation of shaft 29, rotation of the article, and movement of member 65 ceases. Movement of the piston 126 back into the position indicated in Figure 4, due to the engagement of lever 176 with dog 185, causes forward movement of plunger 56 which closes the vacuum line and also moves the rod 51 forwardly to cause the article to be disengaged slightly from the chuck. If an article is again placed on the chuck, the valve 143 will be opened for a short period and the piston 124 will again move to the opposite end of the cylinder from that indicated in Figure 4 and rotation of the article and movement of the member 65 will again occur.

The vents 162 are provided at the various places indicated to permit exhaust of air from one side of the pistons when air is supplied in the cylinders at the opposite side of the pistons 20 so as not to interfere with movement of the pistons. The pistons are normally in such a position that the clutch is in neutral, as indicated in Figure 4, and the vents permit movement of the pistons into such positions. However, the 25 vents are so small that during the time air under pressure is forced through the lines in which they are located, only a comparatively small amount of the air under pressure escapes. The vents also prevent movement of the pistons by accumulating air which might leak past valves 154 or 155 when they are closed.

It will be apparent that one cylinder and piston mechanism causes the clutch to be operated in such a manner that it rotates the article in 35 one direction and moves the member 65 in one direction. The other cylinder and piston mechanism causes the clutch to be operated in such a manner that the article will be rotated in an opposite direction and the member 65 will move 40 in an opposite direction. The two cylinder and piston mechanisms operate alternately, as previously described.

As previously stated, an article is finished during each movement of the screen stencil in one 45 direction. The article and the screen stencil will be in rolling contact with each other along a single line. The screen stencil moves relative to the squeegee and, therefore, the paint will be forced through the stencil onto the article along 50 a line of contact that progressively changes.

When the machine is used for decorating tapered articles, such as the tapered article illustrated in the drawings, the screen stencil 87, as previously stated, is in the form of a segment of 55 a cone. The taper of the cone of which the screen stencil forms a part should be approximately the same as the taper of the article. The end of this screen stencil which has the greater radius of curvature lies adjacent the curved member 65. The center of curvature of the member 65 should lie on the axis of the screen stencil. The opposite ends of the screen stencil will be of 60 different radii of curvature and the difference between the two radii of curvature of the two 65 ends will depend upon the extent of taper of the article. Because the member 65 has its center of curvature lying on the axis of the screen stencil when the member 65 is reciprocated, the screen stencil will move in a rotary path, first in one direction and then the other, about the axis line 70 of the screen stencil. As previously stated, however, tilting of the member 65 also tilts the screen stencil and, consequently, tilts the axis of the screen stencil. The axis of the screen stencil, which is the axis of the cone of which it forms a

part, should be tilted to such an extent that it intersects the axis of the article at a point which will be the common apex of the cone of which the stencil forms a part and the cone which would be formed by continuation of the sides of the 5 article.

As previously stated, if the machine is being used for printing on articles of one taper and then it is desired to use the machine for printing on articles of a substantially different taper, it is 10 necessary to replace the screen stencil with a screen stencil of substantially different taper. The center of curvature of the member 65 should always be on the axis of the screen stencil so that when the member 65 is reciprocated the screen 15 stencil moves in a rotary path about its own axis. Each time a screen of different taper is placed on the machine, it is necessary to adjust the member 65 to a different tilted position in order to change the inclination of the axis of the screen 20 stencil so that it will intersect the axis of the tumbler in the manner previously described. For example, if it is desired to print upon an article of considerably sharper taper than the one illustrated on the machine in Figure 2 of the drawings, it is first necessary to replace the screen 25 stencil with one having substantially the same taper as the new article. However, it will also be necessary to tilt the member 65 rearwardly or to the right (Figure 2) to a greater extent than that 30 illustrated in Figure 2 in order to tilt the axis of the screen stencil so that it will intersect the axis of the tumbler at the common apex of the cone of which the screen stencil forms a part and the cone of which the article forms a part. 35 However, if it is desired to print upon an article of substantially less taper than that illustrated in Figure 2, or in other words, a more nearly cylindrical article, it would be necessary to replace the screen stencil with a stencil of substantially the 40 same taper as the new article and to tilt the member 65 forwardly or to the left to a more nearly vertical position. I preferably provide a few screen stencil supporting members 65 of different 45 radii of curvature, so that when a screen stencil is replaced by a stencil of greatly different taper, the member 65 may be replaced with another member of a curvature more nearly like that of the large end of the stencil and so that the center of curvature of the member 65 will always lie on 50 the axis of the screen stencil.

Because of the fact that the screen stencil is merely supported at one end, it is much easier to feed the article beneath the stencil than would be the case if supporting structures were provided 55 at both ends of the stencil. The segmental screen stencil is supported at its larger end and the article may be fed therebeneath from a point at the opposite or smaller end. This facilitates positioning of the articles beneath the stencil and 60 eliminates the necessity of having conveyors for bringing the articles beneath the screen stencil.

In Figures 13 and 14 I show a modification of my machine. All the mechanism of this machine is the same as that in the preferred form with 65 the exception of the mechanism for reciprocating the screen stencil and the valve mechanism and operating mechanism therefor which is employed for controlling application of vacuum to the vacuum chuck.

As shown in Figure 13 a motor 12a is provided which drives a worm and gear unit 14a. The unit 14a drives a shaft 190 through the medium of belt and pulleys drive 191. The shaft 190 has a disk 192 keyed on its forward end. A rod 193 75

is pivoted eccentrically to the disk at 194. This rod 193 is pivoted at 195 to one end of the stencil supporting member 65. It will be apparent that when the disk 192 is rotated, it will cause reciprocation of the member 65. It will also cause rotation of the article which is mounted on a shaft that carries the gear 63 which is in engagement with rack 64 carried by member 65.

The shaft 190 has a disk 196 keyed on the opposite end thereof. This disk has a rod 197 eccentrically pivoted thereto as at 198. The opposite end of this rod is pivoted at 199 to a rod 200 mounted for movement longitudinally of itself. This rod carries a pair of spaced cams 201. These cams 201 are adapted to engage the outer end of a plunger 56a. This plunger 56a controls a valve 54a substantially like the valve 54 previously described. This valve controls application of vacuum to the vacuum chuck. The plunger 56a is connected to a rod 51a which corresponds to the rod 51 of the preferred form of my machine.

It will be understood that the screen stencil will reciprocate even when an article is not in position on the chuck. In order to keep the squeegee out of contact with the stencil during reciprocation thereof when an article is not in position on the machine in order to lessen wear on the stencil, I provide the structure to be now described. This structure embodies a bell crank lever 202 pivoted to a support as at 203. This bell crank lever has a roller 204 adapted to contact with the outer end of plunger 56a. The upper end of a lever 202 has a rod 205 slidably mounted in an opening therein. A spring 206 is provided around the rear end of rod 205 which tends to swing the lever 202 downwardly around its pivot so that roller 204 will be in contact with the end of plunger 56a. The forward end of this rod is pivotally connected to a finger 207 as at 208. The finger 207 is pivotally connected at 209 to an upstanding support 210 pivoted at 211. The finger 207 is adapted to cooperate with a flat member 212 on the rear end of the squeegee supporting arm 92a.

When an article is in position on the machine, the rod 51a and the plunger 56a are pushed rearwardly. This causes the lower end of the lever 202 to swing upwardly and the upper end thereof to swing rearwardly. Consequently, the rod 205 and the finger 207 will be drawn rearwardly. This causes the finger 207 to be retracted from over the member 212 and, consequently, the arm 92a will be permitted to swing downwardly so that the squeegee will contact with the screen stencil. However, as soon as an article is removed from the machine, the rod 51a and the plunger 56a will be in their forwardmost positions, which will cause the finger 207 to again move forwardly over the member 212 causing the arm 92a to swing upwardly and the squeegee to be raised out of contact with the screen stencil. Thus, when an article is not in position on the machine, the squeegee will be out of contact with the screen stencil.

In Figure 15 I have illustrated a poppet valve unit which facilitates operation of the control for the vacuum chuck and operation of the master valve 143. In the form previously described, when the article is positioned on the chuck, the rod 51 must be pushed rearwardly with sufficient force to cause the plunger 56 to move rearwardly to apply suction to the chuck and the member 186 to swing the lever 188 about its pivot and force plunger 146 forwardly, thereby opening

valve 143. This device works very satisfactorily. However, it may be desirable to provide mechanism for facilitating operation of the valve for controlling application of suction to the vacuum chuck and operation of valve 143 so that only a slight amount of force will be required in positioning the article on the chuck and moving the rod 51 rearwardly. Therefore, I provide the mechanism illustrated in Figure 15 for facilitating opening of the valve 143.

A plunger 56a which corresponds to plunger 56 is provided but in this instance the rod 51a extends rearwardly through the plunger. The rear end of this rod has a sleeve 213 adjustably threaded thereon. This sleeve is slidably mounted in a support 214. The sleeve 213 has an annular shoulder 215 on its forward end. A compression spring 216 surrounds the sleeve 213 and its forward end abuts the shoulder 215 while its rear end abuts the support 214. The plunger 56a and associated parts are exactly the same in all other respects as the plunger 56 and associated parts with the exception that the member 186a, which corresponds to member 186, is mounted on the plunger 56a in such a manner that it will not pivot thereon. The member 188a, which corresponds to the member 188 and is pivoted to the plunger 146a of the valve 143, is adapted to have its upper end 187a engaged by a shoulder 187b on the member 186a. Member 188a is also pivot- ed at 188b.

A poppet valve 217 is provided for operating the valve 143. This poppet valve has a chamber 218 which is always filled with air under pressure through the medium of a line 142d running from the main line 142. This valve has a plunger 219 disposed therein and a spring 220 normally urges this plunger forwardly or in closed position. The forward end of the plunger projects from the valve housing and is adapted to be engaged by a member 221 pivoted at 222. This member 221 has a roller shaft 223 mounted thereon for vertical movement in slots 224. The shaft 223 carries a small roller 225 at each end. The shaft 223 is carried by a vertically extending pin 226 which is bevelled at its upper end as at 227. A compression spring 228 mounted in member 221 normally urges the pin 226, shaft 223 and the rollers 225 upwardly so that they are always in engagement with cam surfaces 229. The upper end of the pin 226 is adapted to be engaged by the shoulder 215 on the sleeve 213 which is carried on the rear end of the rod 51a. A line 143a is connected to the chamber 144 of valve 143 behind the piston 145 and is also connected to the poppet valve at a point in front of the valve seat 219a of the poppet valve 217. A portion 219b on the plunger 219 is normally seated on the seat 219a by the spring 220 to prevent the air from flowing from chamber 218 through line 143a into chamber 144.

In the operation of this mechanism, assuming that the parts are in the positions indicated in Figure 15, if an article is placed on the chuck it will cause the rod 51a to move rearwardly and to slide relative to the plunger 56a. When the rod moves rearwardly the shoulder 215 on sleeve 213 will engage the upper end of the pin 226. This will cause the member 221 to swing about the pivot 222 which, in turn, will cause the rollers to ride downwardly along the inclined cam surfaces 229. The member 221 will contact with the end of plunger 219 and will move the plunger rearwardly allowing the air to flow from the chamber 218 through line 143a to the chamber 144 which will move the piston 145 forwardly.

and open valve 143. Only a puff of air will be permitted to flow past the poppet valve since it will close as soon as the rollers 225 ride downwardly on the cam surfaces 229 a sufficient distance to draw the pin 226 downwardly and to disengage its upper end from the shoulder 215. At this time, the member 221 will again swing forwardly since the spring 220 will urge the plunger 219 forwardly. Furthermore, the poppet valve will be closed. Movement of the piston 145 forwardly also causes the plunger 146a to move forwardly and the member 188a to pivot around the point 188b so that its upper end swings rearwardly. The upper end 187a engages the shoulder 187b and forces the plunger 56a rearwardly. This connects the vacuum line to the vacuum chuck, as described in the other form of the apparatus. The plunger 56a will be returned to its forwardmost position by the mechanism previously described for returning the plunger 56 to its forwardmost position. The valve 143 will automatically close after a short interval. The rod 51 will remain in its rearwardmost position until the plunger 56a is returned to its forwardmost position since the vacuum force of the vacuum chuck is sufficient to resist the tendency of the spring 216 to move the rod into its forwardmost position. However, as soon as the vacuum supply to the chuck is interrupted by movement of the plunger 56a to its forwardmost position, the spring 216 will move the rod into its forwardmost position. During movement of the rod 51a into its forward position the shoulder 215 will strike the upper end 227 of pin 226 which will cause the pin to move downwardly slightly and permit the shoulder to pass.

Thus, it will be apparent that with this mechanism, the rod 51a may be moved rearwardly very easily since the air pressure performs the functions of moving the plunger 146a of valve 143 forwardly and of moving plunger 56a rearwardly, while in the other form of this mechanism it is necessary to apply sufficient force, by placing the tumbler on the chuck in contact with rod 51, not only to move the rod rearwardly but also to move the plunger 56 rearwardly and the plunger 146 forwardly. This mechanism facilitates positioning of the article on the chuck and operation of the machine.

In Figures 17 to 20, inclusive, I have illustrated mechanism which may be employed on my machine for preventing the paint from accumulating at the ends of the stencil. As shown in Figure 20, I provide a unit 230 at each end of the screen stencil 87 for this purpose. Each of the units 230 comprises a main casting 231 which is vertically adjustable on a supporting arm 232 by means of a bolt and slot connection 233. The outer end of the arm 232 is adjustably secured by a bolt and slot connection 234 to a bracket 235 fastened to the screen stencil supporting member 65. The casting 231 has upwardly extending portions 236 at each side having slides 237 formed therein in which slide members 238 operate. These slide members 238 are part of unit 230 which is, consequently, vertically adjustable relative to the casting 231. The unit 230 has a pair of upstanding spaced arms 239 between which is pivoted, as at 240, a bell crank lever 241. One arm 242 of this bell crank lever engages a pin 243 extending between the upper ends of the arms 236 of casting 231. The other arm 244 of the bell crank lever has a latch 245 pivoted to the lower end thereof as at 246.

This latch 245 is adapted to engage a lug 247 on the unit 238. A spring 248 is interposed between the arm 242 of the lever and the latch 245 and normally tends to spread these members apart. A spring 249 is interposed between the base of the unit 238 and the base of the casting 231 and this spring normally tends to cause the unit 238 to slide upwardly on the casting 231.

The unit 238 carries a pair of sleeves 250 in which a pair of rods 251 are mounted for longitudinal movement. These rods have their rear ends connected together by a substantially U-shaped bracket 252. A pair of coil springs 253 are provided in surrounding relation to the forward ends of rods 251. The forward ends of these rods carry an auxiliary squeegee member 254. The springs 253 are disposed between the member 254 and the ends of sleeves 250. These springs normally tend to urge the rods 251 and, consequently, the squeegee member 254 forwardly or towards the center of the screen stencil. A plunger 255 is also slidably mounted on the unit 238. This plunger has its rear end contacting with the lower end of the arm 244 of the bell crank lever 241.

The members 254 will normally be in the position indicated in Figure 19 where they are spaced from the ends of the screen stencil. These auxiliary squeegees 254 extend substantially the entire width of the screen stencil. The blade of each member 254, when the member is in this position, will be out of contact with the screen stencil because the latch 245 is released from lug 247 on unit 238, by contact of member 252 with latch 245, and the spring 249 urges the unit 238 upwardly on the casting 231. However, if the screen stencil is moved to the left until the squeegee 102 contacts with the member 254 at the right hand end of the screen stencil, the member 254 will be moved into the position indicated in Figure 18. During movement into such position, the member 254 will strike the plunger 255 which will cause pivoting of the bell crank lever 241 around the point 240. Since the end of the arm 242 is in engagement with the pin 243 carried by casting 231 this will cause the unit 238 to slide downwardly relative to the casting against the force of the spring 249 until the latch 245 snaps behind the lug 247 which will hold the unit 238 in this position on the casting 231. This will force the blade of the member 254 into contact with the screen stencil as indicated in Figure 18. Now if the screen stencil is moved towards the right, the blade of the member 254 will scrape the paint inwardly towards the center of the stencil because the springs 253 will force the member 254 inwardly towards the center of the screen stencil. During this inward movement of the member 254 the blade is in contact with the screen stencil. When the member 254 nears its inwardmost position, the member 252 will strike the latch 245 and cause it to be released from the lug 247 which will permit the blade of member 254 to move upwardly away from the screen stencil due to the fact that the spring 249 will urge the unit 238 upwardly, which in turn causes bell crank lever 241 to pivot around the point 240. The plunger 255 will also be forced inwardly by movement of the bell crank lever.

Thus, during the inward movement towards the center of the screen stencil, the blade of member 254 will be in contact with the screen stencil and will, consequently, scrape the paint towards the center of the screen stencil. However, during movement of the member 254 to-

wards the extreme end of the screen stencil, its blade will be held upwardly out of contact with the screen stencil so that it will not scrape the paint towards the end of the screen stencil. The squeegee 102 will be raised and lowered as before by the cam units 117 adjacent the ends of the member 86. The means for raising and lowering squeegee 102 and the means for raising and lowering the member 254 will work in properly timed and cooperative relation so that their movements overlap each other, as indicated by the dotted line in Figure 18. Thus, this mechanism will prevent the paint from accumulating at the ends of the screen stencil.

15 It will be apparent from the above description that I have provided a machine having many desirable features. Although this machine is automatic in operation, it is of a very simple and compact structure. It may be operated by a single operator and will have a large capacity. It is easy to operate since it is only necessary for the operator to place an article on the machine to start operation thereof and when the article is finished to merely remove it. The machine is 20 so designed that it may be used in stenciling on tapered articles and there will be no slippage between the surface of the article and the surface of the stencil and, consequently, there will be no smearing of the design or marking applied 25 to the article.

Although the machine may be used for printing on tapered or frusto-conical articles, it may also be used for printing on cylindrical articles. If used for printing on cylindrical articles, the screen need not be in the form of a segment of a cone but should be in the form of a segment of a cylinder. Also, the screen stencil supporting member 65 should lie in a vertical plane 30 and should not be tilted.

40 Various other advantages will appear from the preceding description, the drawings and the following claims.

Having thus described my invention, what I claim is:

45 1. Apparatus of the class described for stenciling on curved articles comprising a curved stencil of segmental form, means for supporting the stencil, means for supporting an article within the arc of curvature of the stencil, and means 50 for moving the stencil relative to the article in first one direction and then the other in a rotary path about its own axis.

55 2. Apparatus of the class described for stenciling on curved articles comprising a curved stencil of segmental form, means for supporting an article within the arc of curvature of the stencil, and means for moving the stencil relative to the article in a rotary path about its own axis.

60 3. Apparatus of the class described for stenciling on articles having a frusto-conical surface comprising a stencil in the form of a segment of a cone, means for supporting the article within the arc of curvature of the stencil, and means for moving the stencil in first one direction and then the other relative to the article and in a rotary path about its own axis.

65 4. Apparatus of the class described for stenciling on articles having a frusto-conical surface comprising a stencil in the form of a segment of a cone, means for supporting the article within the arc of curvature of the stencil, and means for moving the stencil relative to the article and in a rotary path about its own axis.

70 5. Apparatus of the class described for stenciling on curved articles comprising a curved

screen stencil of segmental form, means for supporting the screen stencil, means for rotatably supporting the article within the arc of curvature of the screen stencil, means for moving the screen stencil relative to the article in first one direction and then the other in a rotary path about its own axis, and means for forcing printing material through the stencil onto the article. 5

6. Apparatus of the class described for stenciling on curved articles comprising means for rotatably supporting the article, a curved screen stencil of segmental form, means for supporting the screen stencil, the article being supported inside the arc of curvature of the screen stencil, means for moving the screen stencil relative to the article in a rotary path about its own axis, and means for forcing printing material through the stencil onto the article. 10

7. A machine for decorating articles comprising, in combination, holding means for the article, means for rotating said article about its own axis, a stencil device in the form of a segment of a cone, the article-holding means being so located that the article will be disposed within the arc of curvature of the stencil device, and 15 means for moving said stencil device about the axis of the cone of which it is a segment. 20

8. Apparatus of the class described for stenciling on curved articles comprising means for supporting the article, a curved screen stencil of 30 segmental form, means for supporting the screen stencil, the article being supported within the curved screen stencil, means for moving the stencil and the article relative to each other while maintaining contact therebetween, and means 35 for forcing printing material through the screen stencil onto the article.

9. Apparatus of the class described for stenciling on articles having a frusto-conical surface comprising means for supporting the article, a 40 screen stencil in the form of a segment of a cone, means for supporting the screen stencil, the article being supported within the segmental screen stencil, means for moving the screen stencil first in one direction and then the other in a rotary 45 path about its own axis and relative to the article, and means for forcing printing material through the stencil onto the article.

10. Apparatus of the class described for stenciling on articles having a frusto-conical surface 50 comprising means for supporting the article, a stencil in the form of a segment of a cone, the article being supported within the segmental stencil, and means for moving the stencil first in one direction and then the other in a rotary path 55 about its own axis and relative to the article, the axis of the stencil intersecting the axis of the article at a point which is the common apex of the cone of which the stencil forms a part and the cone which would be formed by continuation 60 of the frusto-conical surface of the article.

11. Apparatus of the class described for stenciling on articles having a frusto-conical surface comprising means for supporting the article, a stencil in the form of a segment of a cone, a 65 supporting structure for the stencil, means for reciprocating the supporting structure to cause the stencil to move relative to the article and about its own axis, the axis of the stencil intersecting the axis of the article at a point which is 70 the common apex of the cone of which the stencil forms a part and the cone which would be formed by continuation of the frusto-conical surface of the article, and means for adjusting said supporting structure to change the inclination of 75

- the axis of the stencil relative to the axis of the article.
12. Apparatus of the class described for stenciling on articles having a frusto-conical surface comprising a stencil in the form of a segment of a cone, means for supporting an article within the arc of curvature of the stencil, and means for moving the stencil relative to the article about its own axis in a rotary path, the axis of the stencil intersecting the axis of the article at a point which is the common apex of the cone of which the stencil forms a part and the cone which would be formed by continuation of the frusto-conical surface of the article. 5
13. Apparatus of the class described for stenciling on articles having a frusto-conical surface comprising a stencil in the form of a segment of a cone, a supporting structure for the stencil, means for supporting an article within the arc of curvature of the stencil, means for reciprocating the supporting structure to cause the stencil to move relative to the article and about its own axis, the axis of the stencil intersecting the axis of the article at a point which is the common apex of the cone of which the stencil forms a part and the cone which would be formed by continuation of the frusto-conical surface of the article, and means for adjusting said supporting structure to change the inclination of the axis of the stencil relative to the axis of the article. 10
14. Apparatus of the class described for stenciling on articles having a frusto-conical surface comprising a screen stencil in the form of a segment of a cone, means for supporting the article within the arc of curvature of the screen stencil, and means for moving the screen stencil relative to the article about its own axis in a rotary path, the axis of the stencil intersecting the axis of the article at a point which is the common apex of the cone of which the stencil forms a part and the cone which would be formed by continuation of the frusto-conical surface of the article. 15
15. Apparatus for stenciling on articles having a frusto-conical surface comprising means for rotating the article about its axis, a screen stencil in the form of a segment of a cone, an arcuate supporting member which carries said screen stencil, means for reciprocating said arcuate supporting member to cause the screen stencil to reciprocate relative to the article, and a squeegee which wipes over the surface of the screen stencil and forces the printing material therethrough onto the article. 20
16. Apparatus for stenciling on articles having a frusto-conical surface comprising means for rotating the article about its axis, a screen stencil in the form of a segment of a cone, an arcuate supporting member which carries said screen stencil, means for reciprocating said arcuate supporting member to cause the stencil to move relative to the article in first one direction and then the other and about its own axis, a squeegee which wipes over the surface of the screen stencil and forces the printing material therethrough onto the article, and means for tilting said stencil supporting member in order to change the position of the axis of said stencil relative to the axis of the article. 25
17. Apparatus for stenciling on curved articles comprising means for rotatably supporting the article, a stencil, means for supporting the stencil adjacent the article, means for rotating the article, means for moving the stencil first in one direction and then the other relative to the article, a single means for controlling both the rotation of the article and movement of the stencil, and means for operating the last means merely by placing the article on its support. 30
18. Apparatus for stenciling curved articles comprising means for rotatably supporting the article, a stencil, means for supporting the stencil adjacent the article, means for rotating the article about its axis, means for moving the stencil relative to the article first in one direction and then the other, a clutch for controlling both the rotation of the article and movement of the stencil, and means for operating the clutch merely by placing the article on its support. 5
19. Apparatus for stenciling curved articles comprising means for rotatably supporting the article, a stencil, means for supporting the stencil adjacent the article, means for rotating the article about its axis, means for moving the stencil relative to the article, a clutch for controlling both the rotation of the article and movement of the stencil, and means for controlling the clutch to cause the article to first rotate in one direction and the stencil to move in one direction relative thereto and to then cause the article to rotate in an opposite direction and the stencil to move in an opposite direction relative to the article. 10
20. Apparatus for stenciling curved articles comprising a chuck for rotatably supporting the article, a stencil, means for supporting the stencil adjacent the article, means for rotating the article about its axis, means for moving the stencil in either direction transversely of the article, a clutch for controlling both the rotation of the article and movement of the stencil, and automatic means operable by placing the article on the chuck for causing the article to rotate in one direction and the stencil to move in one direction relative thereto. 15
21. Apparatus for stenciling curved articles comprising a chuck for rotatably supporting the article, a stencil, means for supporting the stencil adjacent the article, means for rotating the article about its axis, means for moving the stencil in either direction transversely of the article, and automatic means operable by placing the article on the chuck for causing the article to rotate in one direction and the stencil to move in one direction relative thereto. 20
22. Apparatus for stenciling curved articles comprising a vacuum chuck for rotatably supporting the article, a stencil, means for supporting the stencil adjacent the article, means for rotating the article about its axis, means for moving the stencil in either direction transversely of the article, and automatic means operable by placing the article on the chuck for operating the vacuum chuck and for causing the article to rotate in one direction and the stencil to move in one direction. 25
23. Apparatus for stenciling curved articles comprising a vacuum chuck for rotatably supporting the article, a stencil, means for supporting the stencil adjacent the article, means for rotating the article about its axis, means for moving the stencil in either direction transversely of the article, automatic means operable by placing the article on the chuck for operating the vacuum chuck to hold the article thereon and for causing the article to rotate in one direction and the stencil to move in one direction, and means for automatically releasing the article from the chuck. 30
24. Apparatus for stenciling curved articles comprising a chuck for rotatably supporting the article, a stencil, means for supporting the stencil adjacent the article, means for rotating the article about its axis, means for moving the stencil in either direction transversely of the article, and automatic means operable by placing the article on the chuck for operating the vacuum chuck to hold the article thereon and for causing the article to rotate in one direction and the stencil to move in one direction, and means for automatically releasing the article from the chuck. 35

- article, a stencil, means for supporting the stencil adjacent the article, means for rotating the article about its axis, means for moving the stencil in either direction transversely relative to the article, a clutch for controlling both the rotation of the article and movement of the stencil, cylinder and piston mechanism for controlling operation of the clutch, and automatic means operable by placing the article on the chuck for controlling the cylinder and piston mechanism.
25. Apparatus for stenciling curved articles comprising a chuck for rotatably supporting the article, a stencil, a supporting member for the stencil, means for rotating the article about its axis, means for reciprocating the stencil supporting member, a clutch for controlling both the rotation of the article and reciprocation of the stencil supporting member, cylinder and piston mechanism for controlling operation of the clutch, a master valve for controlling flow of fluid to said cylinder and piston mechanism, secondary valves for controlling flow of fluid to said cylinder and piston mechanism, and cams on said stencil supporting member for actuating said secondary valves.
26. Apparatus for stenciling curved articles comprising a chuck for rotatably supporting the article, a stencil, a supporting member for the stencil, means for rotating the article about its axis, means for reciprocating the stencil supporting member, a clutch for controlling both the rotation of the article and reciprocation of the stencil supporting member, cylinder and piston mechanism for controlling operation of the clutch, a master valve for controlling flow of fluid to said cylinder and piston mechanism, said master valve being opened upon placing an article on said chuck, secondary valves for controlling flow of fluid to said cylinder and piston mechanism, and means on said stencil supporting member for actuating said secondary valves.
27. Apparatus for stenciling curved articles comprising a vacuum chuck for rotatably supporting the article, a stencil, a supporting member for the stencil, means for rotating the article about its axis, means for reciprocating the stencil supporting member, a clutch for controlling both the rotation of the article and reciprocation of the stencil supporting member, cylinder and piston mechanism for controlling operation of the clutch, a master valve for controlling flow of fluid to said cylinder and piston mechanism, said master valve being controlled by placing of the article on the chuck, placing of the article on the chuck also automatically operating said vacuum chuck so that the article will be held thereon, secondary valves for controlling flow of fluid to said cylinder and piston mechanism, means on said stencil supporting member for actuating said secondary valves, and automatically operable means for releasing the article from said chuck.
28. In a machine of the type described, a screen stencil, a squeegee contacting with said stencil, said squeegee being mounted for rocking movement about a pivot point, and adjustable means tending to rock the squeegee in one direction.
29. In a machine of the type described, a screen stencil, a squeegee, means for moving the screen stencil relative to the squeegee first in one direction and then the other to cause the squeegee to wipe over the surface thereof, and means for raising the squeegee relative to the screen stencil and then dropping it as the stencil nears the extent of its movement in each direction.

30. An apparatus of the type described comprising a vacuum chuck for supporting the article, a vacuum line, a valve for controlling said vacuum line, a screen stencil movable relative to the chuck, fluid-actuated means for moving said stencil, a master valve for controlling said fluid-actuated means, a control rod adapted to be moved by placing an article on the chuck, and means for causing movement of said rod to operate said first named valve and said master valve.

31. An apparatus of the type described comprising a vacuum chuck for supporting the article, a vacuum line, a valve for controlling said vacuum line, a screen stencil movable relative to the chuck, fluid-actuated means for moving said stencil, a master valve for controlling said fluid-actuated means, a control rod adapted to be moved by placing an article on the chuck, and valve operated means for causing movement of said rod to operate said first named valve and said master valve.

32. In a machine of the type described, a screen stencil, a squeegee, means for moving said stencil relative to said squeegee, means for preventing accumulation of paint at the end of said screen stencil, said means comprising an auxiliary squeegee arranged at the end of said stencil for movement relative thereto, means for moving said auxiliary squeegee towards and from the center of the screen stencil, and means for maintaining the auxiliary squeegee in contact with the screen stencil during movement towards the center thereof but out of contact with the screen stencil during movement away from the center thereof.

33. In a machine of the type described, a screen stencil, a squeegee, means for moving said stencil relative to said squeegee, means for preventing accumulation of paint at the end of said screen stencil, said means comprising an auxiliary squeegee arranged adjacent the end of said stencil and adapted to push the paint from the extreme end of the stencil into the range of movement of the first mentioned squeegee, and means for supporting the auxiliary squeegee for movement relative to said stencil.

34. Apparatus for stenciling on articles having a curved surface comprising means for supporting the article, an arcuate stencil, an arcuate supporting member which carries said stencil in cooperative relation to the article, means for reciprocating said arcuate supporting member to cause the stencil to move relative to the article in first one direction and then the other and about its own axis, and means for tilting said stencil supporting member in order to change the position of the axis of said stencil relative to the axis of the article.

35. Apparatus for stenciling on articles having a curved surface comprising means for supporting the article, an arcuate stencil, means for supporting said stencil at one end only, said means comprising an arcuate supporting member, and means for reciprocating said arcuate supporting member to cause the stencil to move relative to the article in first one direction and then the other.

36. Apparatus for stenciling on articles having a curved surface comprising a chuck for supporting the article, a curved stencil, means for supporting the stencil at one end only, the chuck being arranged so that the article may be applied thereto from a point adjacent the opposite end of the stencil.

37. Apparatus of the class described for stenciling on curved articles comprising a curved

- stencil, means for supporting an article within the arc of curvature of the stencil, and means for moving the stencil relative to the article in a rotary path about its own axis.
- 5 38. Apparatus of the class described for stenciling on articles having a frusto-conical surface comprising a stencil having a frusto-conical surface, means for supporting the article within the arc of curvature of the stencil, and means for 10 moving the stencil relative to the article in a rotary path about its own axis.
- 10 39. Apparatus for stenciling on curved articles comprising means for rotatably supporting the article, a stencil, means for supporting the stencil adjacent the article and in cooperative relation therewith, means for rotating the article first in one direction and then the other, means for moving the stencil first in one direction and then the other relative to the article, and a single means 15 for controlling both the rotation of the article and movement of the stencil in both directions.
- 15 40. Apparatus of the class described for stenciling on curved articles comprising a curved stencil of segmental form, means for supporting the stencil, means for supporting an article in cooperative relation with the stencil, and means for moving the stencil relative to the article supporting means in first one direction and then the other in a rotary path about its own axis.
- 20 41. Apparatus of the class described for stenciling on articles having a frusto-conical surface comprising a stencil in the form of a segment of a cone, means for supporting an article in cooperative relation with the stencil, and means for moving the stencil relative to the article supporting means in first one direction and then the other in a rotary path about its own axis.
- 25 42. Apparatus of the class described for stenciling on curved articles comprising a curved stencil, means for supporting the stencil, means for supporting an article in cooperative relation with the stencil, and means for moving the stencil relative to the article in first one direction and then the other in a rotary path about its own axis.
- 30 43. Apparatus for stenciling on curved articles comprising a curved stencil of arcuate form, a chuck for supporting an article within the arc of curvature of the stencil and against the stencil, and a supporting track for the stencil for movement thereof in a rotary path about its own axis, and means for moving said stencil on said track.
- 35 44. Apparatus for stenciling on curved articles comprising a curved screen stencil of segmental form, a track for supporting the screen stencil, a chuck for rotatably supporting the article within the arc of curvature of the screen stencil, transmission means for moving the screen stencil rela-
- tive to the article in first one direction and then the other in a rotary path about its own axis and a squeegee for forcing printing materials through the stencil onto the article.
45. Apparatus for stenciling on articles having a frusto-conical surface comprising a chuck for supporting the article, a stencil in the form of a segment of a cone, the article being supported within the stencil, a guide track for supporting the stencil for rotative movement, and a transmission for moving the stencil first in one direction and then the other in a rotary path about its own axis and against the article, the axis of the stencil intersecting the axis of the article at a point which is the common apex of the cone of 15 which the stencil forms a part and the cone which would be formed by continuation of the frusto-conical surface of the article.
- 50 46. Apparatus for stenciling curved articles comprising a chuck for rotatably supporting the article for rotation thereof, a stencil, a guide for supporting the stencil adjacent to the article, transmission means for rotating the article about its axis, transmission means for moving the stencil relative to the article first in one direction and then the other, a clutch for controlling both the rotation of the article and the movement of the stencil, and valve means for operating the clutch, said valve means having its control in the chuck 30 in position for actuation by the article when placed on the chuck.
- 55 47. Stenciling apparatus comprising a screen stencil, a squeegee, transmission means for moving said stencil relative to said squeegee, an auxiliary squeegee mounted on the end of said stencil and movable relative to the stencil for engagement in the corner of the stencil, and an actuating device for moving said auxiliary squeegee for pushing the paint from the corner of the squeegee into the range of movement of the first-mentioned 40 squeegee.
- 60 48. Apparatus for stenciling on articles having a curved surface comprising a chuck for supporting the article, a curved stencil, and a curved guide track for supporting the stencil at one end 45 only, said chuck having its article receiving end disposed toward the end of the stencil opposite to the supported end thereof.
- 65 49. Apparatus of the class described for stenciling on curved articles comprising a curved stencil, a chuck for supporting an article within the arc of curvature of the stencil, and a transmission device in driving connection with the stencil for moving the same relative to the article in a rotary path about its own axis.

WILBERT S. WILLIAMS.
